DESIGN FOR A COAT ENSEMBLE

Thomas di Pretore, New York, N. Y.

Application December 13, 1937, Serial No. 73,584

Term of patent 3½ years

To all whom it may concern:

Be it known that I, Thomas di Pretore, a citizen of the United States of America, residing in New York city, in the Borough of Manhattan, county and State of New York, have invented a new, original, and ornamental Design for a Coat Ensemble, of which the following is a specification, reference being had to the accompanying drawing, forming part thereof, wherein,

Figure 1 is a front view of a coat ensemble showing my new design.

Figure 2 is a front view of the suit unit of the coat ensemble shown in Figure 1.

Figure 3 is a rear view of the suit unit shown in Figure 2.

Figure 4 is a rear view of the coat unit of the coat ensemble shown in Figure 1.

The design consists of the combination on the ensemble disclosed of the jacket member embodying the specific seam and pocket arrangement in association with the nailhead embroidered belt, as shown.

I claim:

The ornamental design for a coat ensemble, substantially as shown, and described.

THOMAS DI PRETORE.
